(57) **CLAIM**

I claim the ornamental design for a digital audio player, as shown and described.

DESCRIPTION

FIGS. 1-3 are front perspective views of the digital audio player;

FIG. 4 is a front elevation view thereof;

FIG. 5 is a rear elevation view thereof;

FIG. 6 is a left elevation side view thereof;

FIG. 7 is a right elevation side view thereof;

FIG. 8 is a top plane view thereof;

FIG. 9 is a bottom plane view thereof; and,

FIG. 10 is an enlarged view of "A" of FIG. 1 thereof.

The design is the overall configuration shape ornamentation and pattern of the digital audio player audio player which is made of at least one of synthetic resins, metal, and glass. The design is composed of a volume wheel on the right side which can easily adjust the volume with light scrolling. The design is for listening to high-quality sound of music file playback. The design is created for portability, and a minimized size of digital audio player and amplifier combined. The design is composed of the delicate wavy pattern of the exterior reflecting splendidly when the delicate wavy pattern of the exterior receives light which makes it uniquely sophisticated with a combination of strength and softness.
